UNITED STATES PATENT OFFICE.

EDMUND T. PARTYKA, OF BUFFALO, NEW YORK, ASSIGNOR OF ONE-HALF
TO CHARLES H. KELLOGG, OF SAME PLACE.

DESIGN FOR A RAKE-HEAD.

SPECIFICATION forming part of Design No. 34,936, dated August 13, 1901.

Application filed July 8, 1901. Serial No. 67,549. Term of patent 14 years.

To all whom it may concern:

Be it known that I, EDMUND T. PARTYKA, a citizen of the United States, residing at Buffalo, in the county of Erie and State of New York, have invented and produced a new and original Design for Rake-Heads, of which the following is a specification, reference being had to the accompanying drawings, forming a part thereof.

10 My design for a rake-head is illustrated in the accompanying drawings, in which—

Figure 1 is a plan view of a rake-head embodying the design. Fig. 2 is an end view thereof. Fig. 3 is a perspective view.

15 As shown by the drawings, the leading or essential feature of the design consists in a head having an elongated back formed with separated longitudinal side portions B, which are connected by a series of substantially triangular or V-shaped teeth C, which project therefrom at substantially right angles and are arranged parallel with each other and each diverging from its apex or point toward the back in a plane or direction transversely 20 across the back, so that their greatest width is transversely of the back. Each tooth is shown to be skeleton-like or as composed of

the diverging legs c, connected only at the apex of the tooth and which at their upper ends join with the separated side portions B 30 of the back. The inner or facing edges of the side portions B of the back are made up of a series of inclined faces D, those on one side portion being arranged opposite to and inclined oppositely with respect to those on the 35 other side portion. The inclined faces D diverge from the inner edges of one tooth to the outer edges of the next adjacent tooth, the upper ends of the legs of the teeth forming faces E, connecting the inclined faces D. 40

F indicates upwardly-extending marginal flanges at the outer longitudinal edges of the back, and G indicates a transverse strip at one end connecting the two side portions B.

What I claim is—

45 The design for a rake-head, substantially as shown and described.

Witness my hand this 29th day of June, 1901.

EDMUND T. PARTYKA.
